US00D773743S

(12) **United States Design Patent** (10) Patent No.: **US D773,743 S**
 Tseng et al. (45) Date of Patent: ** Dec. 6, 2016

(54) **DISPOSABLE PLASTIC NARROW-NECK GLOVE**

(71) Applicant: **Inteplast Group, Ltd.**, Livingston, NJ (US)

(72) Inventors: **Ben Tseng**, East Brunswick, NJ (US); **Joe Wang**, Roseland, NJ (US); **Jerry Hsu**, Closter, NJ (US)

(73) Assignee: **Inteplast Group Corporation**, Livingston, NJ (US)

(**) Term: **15 Years**

(21) Appl. No.: **29/534,588**

(22) Filed: **Jul. 30, 2015**

Related U.S. Application Data

(62) Division of application No. 29/454,444, filed on May 10, 2013, now Pat. No. Des. 737,524.
